UNITED STATES PATENT OFFICE.

JOHN KOVACH, OF EAST CHICAGO, INDIANA.

SAND CLEANER.

Application filed January 21, 1922. Serial No. 530,879.

To all whom it may concern:

Be it known that I, JOHN KOVACH, a citizen of formerly Austria-Hungary, now Rumania, residing at East Chicago, in the county of Lake and State of Indiana, have invented certain new and useful Improvements in Sand Cleaners; and I do hereby declare the following to be a full, clear, and exact description of the invention, such as will enable others skilled in the art to which it appertains to make and use the same.

This invention relates to new and useful improvements in sand cleaners and has for its primary object the provision of a device of the above stated character which is adapted to screen the sand for removing trash, stones and other foreign matter so that the sand will be delivered in a fine and clean condition.

Another object of this invention is the provision of means whereby the foreign matter collected by the screen may be removed and deposited laterally from the sand.

A further object of this invention is the provision of a sand cleaner of the above stated character which will be simple, durable and efficient, and which may be manufactured and sold at a comparatively low cost.

With these and other objects in view, as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a side elevation, illustrating a sand crusher and cleaner constructed in accordance with my invention and showing the screen carriage in dotted lines,

Figure 2 is a top plan view, illustrating the device,

Figure 3 is a longitudinal sectional view, illustrating the association of the crushing rollers with the screen, and

Figure 4 is a detail view, illustrating the screen in the act of dumping foreign matter therefrom.

Figure 5 is a detail sectional view illustrating the catch for holding the screen in a closed position,

Figure 6 is an enlarged detail view illustrating the same,

Figure 7 is an enlarged fragmentary sectional view illustrating the catch.

Referring in detail to the drawings, the numeral 1 indicates a supporting frame supported at its corners by legs 2 and is provided at one end with a motor bed 3 on which is mounted a motor or power source 4 of any conventional type and which is provided with a drive shaft 5, the free end of which is journaled in a bearing 6 carried by the motor bed 3. A driven shaft 7 extends parallel with the drive shaft 5 and is journaled in bearings 8 carried by the frame 1 and has an operative connection with the drive shaft 5 by gears 9. The driven shaft intermediate its ends is provided with a sprocket wheel 10 and with a sprocket wheel 11 at one end and which is disposed beyond one side of the frame 1 and engaged by a sprocket chain 12 that is in turn trained over a sprocket wheel 13 secured to a crushing roller shaft 14. The crushing roller shaft 14 extends transversely of the frame and intermediate the ends of the latter and has associated therewith a crushing roller shaft 15 connected to the shaft 14 by gears 16 so that said shafts will rotate in opposite directions. The crushing roller shafts 14 and 15 are journaled in bearings 17 carried by the frame 1 and have secured thereto crushing rollers 18 and the latter are provided with annular crushing ribs 19, the side walls of which are angularly related for the purpose of crushing large particles of sand and also for crushing lumps of sand fed to the rollers from a hopper 20 arranged directly above the rollers and supported by an auxiliary frame 21 mounted on the main frame 1. The hopper 20 is constructed of sections secured together by rivets 21 and the sand containing foreign matter is delivered into the hopper in any manner desired and falls to the crushing rollers whereby all large particles of the sand, stones and the like are crushed and fall onto a screening mechanism 22 located directly under the crushing rollers.

The screening mechanism 22 consists of a rectangular carriage frame 23 provided on its side walls adjacent the ends of the latter with axles 24 on which flanged wheels 25 are journaled and the wheels engage track elements 26 carried by the lower edges of the

frame 1 and which extend inwardly of the side walls of said frame 1. The axles are secured to the carriage frame 23 by bolts. A screen 27, constructed from foraminous material and provided with a marginal flange 28, is hinged to one end of the carriage frame 23, as shown at 29, and supported in engagement with the other end of the frame by a catch 30. Connecting rods 31 are pivotally connected to one end of the carriage frame and to cranks 32 of a crank shaft 33 which is journaled in bearings 34 carried by the lower edge of the frame 1 so that the crank shaft is disposed in a plane 15 below the driven shaft 7 and the crank shaft is provided with a sprocket wheel 35 over which a sprocket chain 36 is trained and the latter is trained over the sprocket wheel 11 for the purpose of imparting rotation to 20 the crank shaft from the driven shaft 7. The rotation of the crank shaft is adapted to impart a reciprocatory motion to the screening device 22 so that the sand and foreign matter falling onto the screen from the 25 crushing rollers will be screened and the large particles of sand and foreign matter will remain on the screen while the clean or fine sand falls through the screen and accumulates in a pile underneath the frame 1.

30 Inclined braces 37 are secured to the frame 1 and to a pair of the legs 2 and are provided with openings 38 whereby a screen supporting roller 39 may be adjusted along the braces. The roller 39 is employed for 35 the purpose of supporting the screen in an inclined position when desiring to dump or remove the foreign matter which has accumulated thereon. To remove the foreign matter from the screen, the carriage or 40 screening mechanism 22 is positioned so that one end of the screen is disposed above the roller 39 and the catch 30 is manually released to permit the screen to swing downwardly in engagement with the roller 39 45 and a movement of the carriage frame towards the end of the frame 1 opposite to where the power source is located, causes the screen to assume a downwardly inclined position and permits the foreign matter 50 thereon to roll off the screen laterally of the pile of sifted sand.

The catch 30 consists of an arm 40 secured to the marginal frame 28 of the screen and projects beyond one end of the frame 55 5 and has pivoted thereto a spring pressed catch arm 41 that engages a keeper 42 carried by the carriage frame so that the free or unhinged end of the screen will be supported in engagement with the carriage 60 frame. The catch arm 41 extends through

a bracket 43 and is engaged by a spring 44 carried by the bracket and the latter is carried by the carriage frame. A handle 45 is provided on the catch arm so that a person may readily disengage the same when desiring to free the screen.

While I have shown and described the preferred embodiment of my invention, it will be understood that minor changes in construction, combination and arrangement of parts may be made without departing from the spirit and scope of the invention as claimed.

Having thus described my invention, what I claim is:

1. A cleaner comprising a frame, a carriage reciprocally mounted on the frame, a hinged screen carried by said carriage, a catch for holding the screen in a carriage closing position, and a transverse roller adjustably secured to the frame and adapted to be engaged by the screen when freed to cause the screen to assume a downwardly inclined position on the movement of the carriage in one direction.

2. A cleaning mechanism comprising a frame, a carriage reciprocally mounted on the frame, a hinged screen carried by said carriage, a catch for holding the screen in carriage closing position, a brace connecting said frame with one of its supporting legs, said brace having perforations therein, a transverse roller adjustably mounted in the perforations of said brace and adapted to be engaged by the screen when the latch is released, to cause the screen to assume a downward inclined position on movement of the carriage in one direction, whereby the contents of the screen will be discharged at a point a distance from the point of discharge of material passing through the screen.

3. A reciprocating cleaning screen comprising a wheeled carriage, a screen hinged to said carriage at one end thereof, a catch for holding the screen in closed position, said catch being located at the opposite end of said carriage, and comprising a pivoted arm having connection with said hinged screen at its free end, a spring to urge said pivoted arm into engagement with a lug carried by said carriage, and manually operated means to release said latch from said lug.

In testimony whereof I affix my signature in presence of two witnesses.

JOHN KOVACH.
